UNITED STATES PATENT OFFICE.

HENRY P. CLAUSEN, OF MOUNT VERNON, NEW YORK, ASSIGNOR TO WESTERN ELECTRIC COMPANY, INCORPORATED, OF NEW YORK, N. Y., A CORPORATION OF NEW YORK.

MACHINE-SWITCHING TELEPHONE-EXCHANGE SYSTEM.

1,277,385.

Specification of Letters Patent. Patented Sept. 3, 1918.

Application filed February 5, 1917. Serial No. 146,702.

To all whom it may concern:

Be it known that I, HENRY P. CLAUSEN, a citizen of the United States, residing at Mount Vernon, in the county of Westchester and State of New York, have invented certain new and useful Improvements in Machine-Switching Telephone-Exchange Systems, of which the following is a full, clear, concise, and exact description.

This invention relates to machine switching telephone exchange systems with subscriber's control, and its object is to provide in a system of this character a circuit arrangement whereby the calling party, failing to secure a response from the called party upon whose line he has set a connector switch, may operate a signaling device before an attendant at the central office who may then communicate with such calling party.

The signaling device also serves to apprise the attendant of an unstandard condition existing in the connector circuit, and is automatically operated upon the creation of such condition.

The invention is illustrated in the accompanying drawing which shows diagrammatically a connection between two subscribers, the circuits of a connector switch embodying the principles of this invention being shown in full.

In accordance with this invention, a signaling device is associated with each connector switch. A circuit for operating the signaling device extends from a circuit closing device, closed when the connector switch is set, through a contact of the stepping relay to the signaling device. In association with this circuit is an electromagnetic responsive device which will be actuated if the stepping relay vibrates its armature after the connector switch is set.

If the armature of the stepping relay comes to rest after such vibration in the position which it normally occupies during the use of the connector switch, a circuit for operating the signaling device in a way to show that connection with an attendant is desired by the calling subscriber will be maintained from a contact of the electromagnetic responsive device through said stepping relay armature to the signal, until an attendant answers the call. If, however, the

calling subscriber abandons the call while the called subscriber fails to replace his receiver on the hook, the connector switch will not be released, but the armature of the stepping relay at its alternate contact will close a circuit for operating the signaling device in a way to indicate the existence of this unstandard condition of the connector switch, and the attendant may communicate with the called subscriber or release the switch.

The calling subscriber's substation is shown at A connected through a line finder indicated diagrammatically at 3, and selector switches 4 and 5, to the connector switch having brushes 7, 8 and 9. B indicates the substation of a called subscriber.

The invention will be more readily understood from the following description of the operation of the system.

When the subscriber at A removes his receiver from the hook, the line finder 3 automatically connects his line to the first selector switch 4. The subscriber now sends, with his dial, a series of impulses which sets the switch 4 on the terminals leading to the second selector switch 5. The subscriber dials again to set the brushes of the selector 5 on the terminals leading to the connector switch in whose contact bank terminates the line of the desired subscriber. As soon as the switch 5 has been set a circuit is closed from ground, lower winding of relay SR, back contact and inner lower armature of relay CS, lower brushes of switches 5, 4 and 3, substation A, middle brushes of switches 3, 4 and 5, upper armature and back contact of relay CS, through the upper winding of relay SR, to battery and ground. The relay SR is energized and closes a circuit for slow relay 10 from ground, inner armature and front contact of relay SR, through the winding of relay 10 to battery and ground. The relay 10 is slow to release, remaining energized during the sending of impulses, and places ground through its upper armature and front contact on the release trunk 6 so as to prevent the release of the line finder and selector switches.

The subscriber now dials again, causing the armature of the relay SR to vibrate. Each time relay SR retracts its armature a circuit is closed from ground, inner armature and back contact of relay SR, lower

armature and front contact of relay 10, contact and middle lower armature of relay 12, winding of slow relay 11, through the winding of the primary magnet PM and side-switch wiper 13 (position 1), to battery and ground. The magnet PM, being intermittently energized, steps the wipers 7, 8 and 9 to the group of terminals in which the line of the called subscriber terminates. The 10 slow relay 11 holds up its armature during each series of impulses and closes a circuit from ground, armature and front contact of relay 11, through the winding of the side-switch escape magnet Esc., to battery and ground. At the close of this series of impulses, when the circuit for the relay 11 remains open, it breaks the circuit for the magnet Esc., which, in deenergizing, advances the wipers of the side switch to their 15 second position.

The subscriber now sends the final series of impulses which completes, as before, the circuits for slow relay 11 and for the escape magnet Esc. Each time that the relay SR is deenergized a circuit is closed for the secondary magnet from ground, inner armature and back contact of relay SR, lower armature and contact of relay 10, contact and middle lower armature of relay 12, winding of relay 11, through the winding of the secondary magnet SM, wiper 13 (position 2), to battery and ground. The magnet SM sets the brushes of the connector switch on the terminals of the wanted 20 line.

If the wanted line is busy ground will be found on the test terminal and a circuit will be completed through the brush 9, wiper 14 (position 2), back contact and inner armature of test relay T, through the winding of relay T, back contact and armature of relay 11, through the winding of the magnet Esc., to battery and ground. The magnet Esc. will, therefore, be locked up 25 and will prevent the advance of the side switch into its third position. The test relay T, in energizing, closes a locking circuit for itself from ground, lower spring of primary off-normal contact PON, inner armature and front contact of relay T, through the winding of the relay T, armature and back contact of relay 11, winding of the magnets Esc. to battery and ground. A circuit is also closed from ground at the 30 secondary of the transformer Bz, lower armature and contact of relay T, wire 2, lower winding of relay CS to ground. As a result of this circuit, a distinctive busy tone is sent out over the calling line and the subscriber hangs up his receiver, causing the release of the switches in a manner to be described.

If the wanted subscriber is idle, no ground being found by the test brush 9, the magnet Esc. deenergizes when the relay 11 falls

back at the close of the final series of impulses, and the side-switch wipers are advanced into their third position. An energizing circuit is thereupon closed for the relay 12 from grounded battery, wiper 13 (position 3) winding of relay 12, wiper 14 (position 3), to ground. A circuit for intermittently energizing the ringing relay RR is also closed from grounded battery, wiper 15 (position 3), bottom armature and contact of relay 16, interrupter I, winding of relay RR to ground. Each time the relay RR attracts its armature a circuit is closed from an alternating current source 25, front contact and armature of relay RR, back contact and inner lower armature of relay 16, innermost lower armature and contact of relay 12, brush 8 through the substation B, brush 7, contact and upper armature of relay 12, outer upper armature and back contact of relay 16, through the lower winding of the relay 16 to ground. The signaling apparatus at the substation B will be actuated in this circuit, but the relay 16 is marginal and will not energize at this time. 90

If at this time the calling subscriber becomes impatient and desires connection with an attendant, he may, by dialing or by momentarily depressing his switchhook, vibrate the armature of the stepping relay SR, which, in retracting its armatures, will complete a circuit from grounded battery, winding of relay 17, resistance R, contact 26, lower armature and back contact of relay SR, wire 19, through the bottom armature and contact of relay 12 to ground. The relay 17, in energizing, locks up from grounded battery, winding of relay 17, resistance R, left-hand armature and front contact of relay 17, wire 19, bottom armature and contact of relay 12 to ground. When the subscriber ceases dialing, or operating his switchhook, and the armatures of relay SR return to their attracted position, a circuit is completed from ground through the interrupter 18, right-hand armature and front contact of relay 17, front contact and lower armature of relay SR, through the lamp L to battery and ground. 100

The lamp L, or any other convenient signaling device or annunciator which may be substituted, is located at an attendant's position and will be intermittently actuated over the circuit just traced until an attendant answers the call. The sleeve of the attendant's plug P is directly connected to battery so that, in inserting the plug into the jack J, the relay 17 will be shunted, and, in deenergizing, will discontinue the signal. 110 The attendant may now converse with the calling subscriber, giving him any information desired. 120

When the called subscriber answers he closes at his switchhook a path of low re- 130

sistance from the alternating current source and front contact of relay RR, or grounded battery and back contact of relay RR, through the armature of relay RR, back 5 contact and lower inner armature of relay 16, innermost lower armature and contact of relay 12, brush 8, substation B, brush 7, contact and upper armature of relay 12, outer upper armature and back contact of 10 relay 16, through the lower winding of the ringing trip relay 16 to ground. The ringing trip relay 16 is energized and opens at its bottom armature the circuit for the relay RR so that ringing ceases. The relay 16 15 is locked up from grounded battery, upper winding of relay 16, inner upper armature and contact of relay 16, lower spring of contact PON to ground. The relay 16 also completes the talking circuit between sub- 20 stations A and B, the talking current for A being supplied through the windings of the relay SR, while current for station B is supplied through the windings of the called supervisory relay CS, which is held 25 energized until the called subscriber replaces his receiver on its hook. If at any time during the conversation the calling subscriber desires the attention of an attendant, he may, by dialing, cause the energization of the relay 17 and the consequent 30 actuation of the lamp L in the manner previously described.

At the close of the conversation the release of the line finder and selectors will be accomplished when the deenergization of the 35 relay 10 removes the ground from the release relay 10, but the connector will not be released until both parties have hung up. If both parties hang up a circuit will be closed 40 from ground, upper armature and back contact of relay 10, upper spring of contact PON, bottom armature and contact of relay CS, through the winding of the release magnet Rel., to battery and ground, and the 45 release magnet being energized, will restore the connector switch to normal. If, however the called subscriber fails to replace his receiver on its hook, the called supervisory relay CS remains energized and holds 50 open at its bottom armature the circuit for the release magnet. Whenever this condition occurs the lamp L will be actuated as soon as the calling subscriber hangs up, the circuit being from grounded battery, lamp 55 L, bottom armature and back contact of relay SR, wire 19, bottom armature and contact of relay 12 to ground. As the inter-rupter 18 is not included in this circuit, the lamp will burn steadily, thus notifying an 60 attendant of the existence of this unstandard condition. The attendant may now converse with the subscriber at B, or, if the subscriber has left the instrument, she may place a howler on the line, and, after a reasonable 65 time, release the connector switch.

It is thus to be noted that two distinct methods for operating the lamp L are provided, the method of operation being determined by the position of the bottom armature of the relay SR.

70

What is claimed is:

1. In a machine switching telephone system, the combination with telephone lines and automatic switches including a connector switch for interconnecting said lines, 75 of an annunciator associated with said connector switch, means actuated by a calling subscriber when said switch has been set for actuating said annunciator in a characteristic manner, and means for automatically actuating said annunciator in a different manner during the existence of a certain unstandard condition in said associated connector switch.

2. In a machine switching telephone system, the combination with telephone lines, 85 automatic switches including a connector switch for interconnecting said lines, means including a stepping relay for setting said switches, and an attendant's position, of 90 an annunciator at said position, an electromagnetic device, a circuit controlled thereby for actuating said annunciator in a characteristic manner, a switch arranged to be closed when the connector is in its set position, a circuit controlled by the calling subscriber for operating said device including said switch, and a contact of the stepping relay, an alternative circuit for operating said annunciator in a different manner, 95 said circuit including said switch and the alternate contact of the stepping relay.

3. In a machine switching telephone exchange system, the combination with telephone lines, means including a connector 105 switch for interconnecting said lines, means including a stepping relay for setting said connector switch, an attendant's position, an annunciator thereat, a circuit for said annunciator including a front contact of 110 said stepping relay, a relay for closing said circuit, a switch closed when the connector is set on the called line and a circuit for said last mentioned relay including a back contact of said stepping relay and 115 said switch.

4. In a machine switching telephone system, calling and called subscribers' lines, means including a connector switch for interconnecting said lines, a stepping relay 120 for said connector, a signaling device associated with said connector switch, and means associated with said connector switch and dependent upon the operation of said stepping relay for causing the said signaling 125 device to operate continuously or intermittently.

5. In a machine switching telephone system, calling and called subscribers' lines, 130 automatic switches for connecting said lines,

a signaling device associated with one of said switches and means associated with said switch and controlled by a momentary interruption of the talking circuit at a connected station to cause said signaling device to operate intermittently and controlled by the permanent interruption of the talking

circuit to cause the continuous operation of said signaling device.

In witness whereof, I hereunto subscribe my name this 3rd day of February, A. D. 1917.

HENRY P. CLAUSEN.
